UNITED STATES PATENT OFFICE.

FRANCIS B. RILEY, OF NEWTON, MASSACHUSETTS, ASSIGNOR TO HEYWOOD-WAKEFIELD COMPANY, OF BOSTON, MASSACHUSETTS, A CORPORATION OF MASSACHUSETTS.

APPARATUS FOR PRODUCING IMITATION BASKET FABRICS.

Application filed September 23, 1920. Serial No. 412,336.

To all whom it may concern:

Be it known that I, FRANCIS B. RILEY, a citizen of the United States, residing at Newton, in the county of Middlesex and 5 Commonwealth of Massachusetts, have invented a new and useful Improvement in Apparatus for Producing Imitation Basket Fabrics, of which the following, together with the accompanying drawings, is a specification.

The present invention relates generally to the production of a fabric suitable for use in the manufacture of baskets, furniture, baby carriages and the like. Such a 15 fabric, consisting of reed, paper reed, wicker or other similar material, ordinarily presents a series of spaced elements or stakes of considerable rigidity, with interwoven strands of similar material but usually of 20 less rigidity in close, compact and unspaced arrangement—both the stakes and the strands differing greatly from the threads of a textile fabric in that they offer considerable resistance to bending, twisting or 25 kinking.

The present invention contemplates the simple and easy production of a fabric closely resembling the stake and strand fabrics of this class by the utilization of sheets 30 of heavy paper, cardboard, fiberboard, or other similar flexible and durable material, the latter serving, as hereinafter described, as the warp material, for interweaving with the spaced stakes. The invention is fully 35 set forth in the following description, reference being had to the accompanying drawings, in which—

Fig. 1 is a diagrammatic plan view showing the fabric in process of formation.

Fig. 2 is a view in side elevation of the 40 parts shown in Fig. 1.

Figs. 3 and 4 are detail views showing modifications in the form of the devices for operating on the sheet of warp material.

Figs. 5 and 6 are similar views showing 45 other modifications in the form of these devices.

Fig. 7 is a plan view of the fabric as produced by the herein described invention.

Like reference characters refer to like 50 parts in the different figures.

Referring to Figs. 1 and 2, there is illustrated a continuous sheet 1 of suitable material, such as heavy paper, cardboard, fiber-

board or the like, which is in process of being formed, so to speak, into the warp of the woven fabric, by passage between co-operating sets of scoring and deflecting devices, as hereinafter described. The scoring devices here take the form of coacting 55 revoluble rolls 2 and 3, carried by shafts 4 and 5 respectively that are driven in unison, these rolls serving for the advancement of the sheet 1, and also, by means of their spaced peripheral scoring ridges 6 and 7, imparting to the sheet, on each side thereof, a plurality of longitudinal scores. These scores preferably do not completely sever the material of the sheet 1, but on the other hand, sufficiently weaken it so as to 60 facilitate the subsequent opposite deflection of adjacent portions thereof, in the process of forming the fabric.

The scored sheet, as indicated at 8, passes in continuous form to the deflecting or 65 forming devices, here shown as cooperating rotatable elements 9 and 10 carried respectively by shafts 11 and 12. Each forming device 9 and 10 is made up of a plurality 70 of disks or plates 13 which are secured side by side upon the shafts 11 and 12, and correspond in number and width to the spaces between the scoring ridges 6, 6 and 7, 7 on the rolls 2 and 3. In other words, the 75 adjacent disks or plates 13 line up with the adjacent strips of material in the sheet 8 between the scores; each disk or plate 13 presents on its periphery a plurality of cam projections 14, alternating with depressions 15, and the alternate disks 13 of each element 9, 10 are angularly displaced in the 80 manner shown in Fig. 2, so that the aligned cam projections 14, 14 of every alternate disk or plate 13 on one shaft 11 come into 85 matching relation with the aligned depressions 15, 15 of the corresponding alternate disks or plates 13 on the other shaft 12. In the same way the depressions of the first 90 set of disks or plates match up with the cam projections of the other set of disks or plates, as the shafts 11 and 12 are rotated in unison to advance the scored sheet 8 therebetween. To this end, the cooperating 95 opposite disks or plates 13 on the shafts 11 and 12 have their edges spaced apart substantially the thickness of the sheet.

As the scored sheet 8 is advanced by the 100 cooperating revoluble elements 9 and 10,

each longitudinal portion thereof between the parallel scores is severed at intervals along the scores by the forcible deflection, first in one direction and then in the opposite direction, effected by the cam projections 14 of the disks or plates 13. In other words, with reference to the production of a fabric of regular weave, here selected for purposes of illustration, it will be understood that when the cam projections 14 and depressions 15 reach their cooperating positions, every alternate portion of the sheet material between scores will be deflected in one direction, while the other portions will be deflected in the other direction, on opposite sides of the plane of movement of the sheet 8.

As a consequence, the material of the sheet emerges from between the elements 9, 10 in the form shown at 16, Figs. 1 and 2; the longitudinal strips 17 between the scores present a series of alternate raised and depressed portions with points of union, preferably where they cross each other, as indicated at 18. The strips 17, especially when the material, such as fiberboard, has sufficient inherent stiffness, will retain their deflections after leaving the elements 9 and 10; with material that does not sufficiently possess this characteristic, but tends to spring back after deflection, it is found desirable to wet it before the deflection is imparted; this causes such material to retain its deflected form after it leaves the elements 9, 10.

As thus deflected, the series of strips 17 present a succession of openings or spaces 19 across the width of the sheet for the insertion of stakes 20; the latter may be pushed into place by hand if desired, or in any other suitable way, as by means of a reciprocating jig 21. The insertion of the stakes 20 in the regularly spaced intervals presented by the sheet as it emerges in the form shown at 16 completes the fabric, as far as interweaving of the stakes with the sheet material is concerned. If desired, the material, with the stakes thus interwoven, may be passed between compressing rolls 22 and 23 for the purpose of firmly retaining the stakes in place; this procedure is preferable, especially when the sheet 1 has been moistened, but when the sheet possesses the requisite inherent resiliency, the pressing step may be dispensed with.

In order still further to simulate the appearance of woven reed, a form of the scoring and deflecting instrumentalities may be availed of such as shown in Figs. 3 and 4; the scoring rolls 24 and 25, by reason of the circular grooves 26 in the former, are designed to exert sufficient pressure to deform the material, causing its presentation to the deflecting elements 27 and 28 in a series of substantially half-round strips, somewhat

of the nature of split reed. Suitable peripheral grooves 29 in the corresponding set of disks or plates 30 of the deflecting device, Fig. 4, are provided, when scoring and deforming rolls such as shown in Fig. 3 are used, the operation of the deflecting and severing means being precisely the same as heretofore described.

The simulation to reed fabric may be carried still further by the provision of scoring and deflecting means such as shown in Figs. 5 and 6, where the scoring rollers 31 and 32 have cooperating peripheral grooves 33 and where the deflecting and severing disks or plates 34 have cooperating peripheral grooves 35.

Fig. 7 shows a section of complete fabric, and illustrates the manner in which variations of design may be readily obtained. For such a fabric, it is only necessary to vary the distance between the peripheral ridges on the scoring rolls in order to obtain the strips of different widths, with corresponding variations in the thickness of the deflecting plates or disks. Various other modifications in the form and design of the completed fabric can readily be obtained by changes in the form and arrangement of the cam projections on the deflecting elements, as well as in the form and arrangement of the inserted stakes.

From the foregoing, it is apparent that the invention provides a particularly advantageous method for producing a fabric which is very similar to hand woven reed fabrics; using plain sheets of cardboard, fiberboard, or any other similar durable flexible material. The fabric can be formed quickly and continuously and with a minimum of effort on the part of the operator, owing to the extreme simplicity of the mechanism employed. The production of such a fabric is susceptible of numerous variations and modifications without departing from the spirit and scope of my invention as defined in the appended claims.

I claim:

1. In a machine of the class described, a pair of rotatable cylinders, one at least having continuous cutting portions disposed around the cylindrical surface, the edge of each portion being continuous and entirely in a right section of said cylinder, the said cylinder being adapted to score a sheet of flexible material in a series of continuous parallel lines, and shed forming means comprising a pair of shafts with a plurality of cams mounted on each shaft adapted to break the scored sheet into a number of sheds for the insertion of stakes in spaced relation.

2. In a machine of the class described, a pair of rotatable cylinders, one at least having its cylindrical surface destroyed by a contiguous series of concave grooves, each

- groove having a center on the axis of the said cylinder, and the plane of each groove being at right angles to the axis of the said cylinder, the two cylinders being adapted to 5 score one surface at least of a sheet of flexible material, in straight, parallel, unbroken lines, and shed forming means comprising a pair of shafts with a plurality of cams mounted on each shaft adapted to break 10 the scored sheet into a number of sheds for the insertion of stakes in spaced relation.
3. In a machine of the class described, a pair of rotatable cylinders, one at least having its cylindrical surface destroyed by a 15 contiguous series of concave grooves, each groove having a center on the axis of the said cylinder, and the plane of each groove being at right angles to the axis of the said cylinder, the two cylinders being adapted to 20 score and rib one surface at least of a sheet of flexible material, in straight, parallel, unbroken lines, and shed forming means comprising a pair of shafts with a plurality of cams mounted on each shaft adapted to 25 break the scored sheet into a number of sheds for the insertion of stakes in spaced relation.

FRANCIS B. RILEY.
